F. B. STOBER.
ANTIFREEZING APPLIANCE.
APPLICATION FILED JULY 2, 1913.

1,108,806.

Patented Aug. 25, 1914.

UNITED STATES PATENT OFFICE.

FLOYD B. STOBER, OF BYERS, COLORADO.

ANTIFREEZING APPLIANCE.

1,103,806.

Specification of Letters Patent. Patented Aug. 25, 1914.

Application filed July 2, 1912. Serial No. 777,013.

To all whom it may concern:

Be it known that I, FLOYD B. STOBER, a citizen of the United States, residing at Byers, in the county of Arapahoe and State 5 of Colorado, have invented new and useful improvements in Antifreezing Appliances, of which the following is a specification.

The primary object of this invention is the provision of means for preventing the freezing 10 of liquid in a tube or pipe extending above the frost lining and exposed to cold weather.

The invention contemplates a valve located in the length of the tube or pipe and 15 adapted to be controlled in its movements by the flow of the water or the liquid through such tube or pipe, said valve in one position closing waste openings and in another position interrupting the back flow 20 of the water so as to hold the same at a predetermined height in the tube or pipe at a safe point below the frost lining.

A further purpose of the invention is the provision of means which may be utilized 25 for coupling section of the tube or pipe, said coupling being provided with the waste opening and the automatic valve for controlling the discharge of the water through the waste opening.

30 The invention consists of the novel features, details of construction and combination of parts, which hereinafter will be more particularly set forth, illustrated in the accompanying drawings, and pointed out in 35 the appended claims.

Referring to the drawings, forming a part of the specification, Figure 1 is a sectional view of an appliance embodying the invention showing the position of the valve 40 when seated and the waste openings uncovered. Fig. 2 is a view similar to Fig. 1 showing the position of the valve when unseated and the waste openings closed. Fig. 3 is a top plan view of the lower member 45 of the coupling showing the guide in position. Fig. 4 is a detail perspective view of the valve. Fig. 5 is a section on the line x—x of Fig. 1.

Corresponding and like parts are referred 50 to in the following description, and indicated in all the views of the drawings, by the same reference characters.

The tube or pipe through which the liquid 55 or water is discharged by means of a pump or other appliance is designated by the reference numeral 10. A chamber or valve

body is located in the length of the tube or pipe and partakes of the nature of a coupling and comprises members 17 and 18 which are connected by means of a screw 60 thread joint 24 each of the members 17 and 18 making screw thread connection with the sections or parts comprising the tube or pipe 10. Lateral openings 23 are formed in the sides of the member 17 and constitute outlets for the waste water. The pump rod is indicated at 11 and operates through a guide 12, the latter being provided with arms 16 which are clamped between the opposing ends of the members 17 65 and 18. The end of the member 18 is notched to form seats in which the outer ends of the arms 16 are fitted. The pump rod 11 is adapted to operate through an opening formed in the guide 12 and in order to prevent any passage of water 70 through the opening of the guide 12 the same is recessed in its upper end and receives packing 21 which is held in place by means of a nut or gland 22. A space is 75 formed between the guide 12 and the inner wall of the member 18 for the passage of the liquid or water in its discharge through the tube 10. This space is controlled by means of a valve 13 the latter obtaining a seat 80 upon the upper end of the guide and arms. When the valve is seated as indicated in Fig. 1 the space between the guide 12 and member 18 is closed, thereby preventing air 85 passing into that part of the tube below the valve with the result that the water is held 90 therein. When the pump is in operation to cause a discharge of water through the tube 10 the valve is unseated and occupies the position substantially as indicated in Fig. 95 2. The valve 13 is provided with wings 14 which extend upwardly and possess a slight spring action to press lightly against the sides of the member 17. The wings 14 close the outlets 23 when the valve is elevated as indicated most clearly in Fig. 2. To hold 100 the valve and wings thereof in proper position grooves 15 are formed in the walls of the member 17, said grooves receiving the wings 14, thereby preventing relative turning of the valve and insuring the outlets 23 being closed when the valve is elevated.

The valve 13 and wings 14 preferably constitute parts of a single blank. As hereinbefore indicated the parts 17 and 18 constitute elements of a chamber or body which receives the guide 12 and valve 13 and

which also serves as coupling means for connecting sections of the tube or pipe 10.

In the operation of the invention the valve 13 is held elevated by the flow of water 5 through the tube or pipe 10 when the pump is in operation, the waste of which, 23, being closed at such time. When the pump is at rest the valve 13 gravitates and is assisted in its downward movement by the 10 weight of the water above such valve and which tends to escape. When the valve 13 becomes seated as indicated in Fig. 1 the waste outlets 23 are uncovered and the water above such valve has an unobstructed 15 passage through the outlets 23 with the result that the upper portion of the tube is completely drained thereby preventing the water from standing therein and the freezing in extreme cold weather.

20 From the foregoing description, taken in connection with the accompanying drawings, the advantages of the construction and of the method of operation will be readily apparent to those skilled in the art to which the invention appertains, and while I have 25 described the principle of operation of the invention, together with the device which I now consider to be the best embodiment thereof, I desire to have it understood that 30 the device shown is merely illustrative, and that such changes may be made when desired as are within the scope of the claims appended hereto.

I claim:

35 1. In combination, a pump tube having a waste outlet at a point below the frost line, a valve located in the length of such tube and controlled in its movements by the flow of water through the tube and a wing carried by such valve and adapted to close the waste outlet when the valve is unseated and to uncover the waste outlet when such valve is seated.

2. In combination, a pump tube having 45 a valve seat in its length and a waste outlet near such valve seat, a valve arranged within the tube and adapted to close upon the valve seat and a wing carried by the valve and adapted to close the waste outlet when 50 the valve is unseated, said valve being controlled in its movements by the flow of water through the tube.

3. A pump tube having a valve seat and a waste outlet near the valve seat and at 55 a point below the frost line, said tube being further provided with a vertical groove between the valve seat and waste outlet, a valve for closing upon the valve seat and a wing carried by the valve and adapted to

operate in the before mentioned vertical 60 groove and adapted to close the waste outlet when the valve is unseated.

4. A pump tube having a valve seat, opposed waste outlets and relatively vertical 65 grooves, a valve for closing upon the valve seat and wings projecting from the valve and arranged to operate in the said vertical grooves to close the waste of which when the valve is unseated.

5. In an anti-freezing means of the character specified, the combination of a chamber having an inner valve seat and a waste opening, a guide located within the chamber to receive and direct the pump rod in its movements, a valve for closing upon the 75 valve seat and a wing carried by the valve and adapted to close the waste outlets.

6. In an anti-freezing device of the character set forth the combination of two members, one of such members having a waste 80 outlet, a guide adapted to be clamped between the members and forming an inner valve seat, a valve for closing upon the valve seat and a wing carried by the valve and adapted to close the waste outlet. 85

7. In combination, two members adapted to be coupled, one of such members having a waste outlet, a guide provided with arms which are clamped between the said members, said guide providing an inner valve 90 seat, a valve for closing upon the valve seat and a wing carried by the valve and adapted to close the waste outlet.

8. In an anti-freezing device of the nature hereinbefore specified, the combination of a 95 chamber comprising members which are adapted to be connected by means of a screw thread joint, one of said members having opposed lateral waste outlets and inner vertical grooves in line with such outlets, a 100 guide having an outer portion clamped between the two members of the chamber and forming a space for the flow of water through the chamber and providing an inner valve seat, a valve for closing upon the 105 valve seat and controlled in its movements automatically by the flow of water through the chamber and spring wings carried by the valve and adapted to operate in the before mentioned grooves to close the waste 110 outlets.

In testimony whereof I affix my signature in presence of two witnesses.

FLOYD B. STOBER.
